UNITED STATES PATENT OFFICE.

WILLIAM T. MCCOOK, OF RICHMOND, VIRGINIA.

PNEUMATIC HAMMER.

SPECIFICATION forming part of Letters Patent No. 719,027, dated January 27, 1903.

Application filed January 30, 1902. Serial No. 91,825. (No model.)

To all whom it may concern:

Be it known that I, WILLIAM T. MCCOOK, a citizen of the United States, and a resident of Richmond, in the county of Henrico and State 5 of Virginia, have invented certain new and useful Improvements in Pneumatic Hammers, of which the following is a specification.

My invention relates to that class of tools known as "pneumatic or automatic hammers or impact-tools" and which are used for chipping, riveting, calking, and similar operations; but the principles which my invention embodies may be also applied to machines used in other arts, such as hot-air engines, pumps, steam and gas engines, &c.

In automatic hammers and similar tools and engines it is desirable that the motive fluid shall be used in as economical a manner as possible, that the reciprocating parts shall be 20 properly cushioned at the ends of their strokes, that the use of the tool may be attended with as little discomfort to the operator as possible, that the tool may be always ready for use, and that the force of the blow delivered by 25 and the length of stroke of the hammer may be under the control of the operator. The force of the blow delivered by the hammer is regulated to some extent in some hammers by wire-drawing the air or other motive fluid; 30 but this method is not always a satisfactory one, particularly in the case of portable pneumatic hammers. A more desirable method by which to regulate the force of the blow is that in which the length of the stroke of the 35 reciprocating piston or hammer is regulated, and such a regulation, combined with that obtainable by wire-drawing the motive fluid, enables the operator to obtain any force of blow between the limits of absolute rest and 40 the heaviest blow of which the hammer is capable. It is now the general practice to use different hammers having different lengths of stroke for different classes of work. This means a large outlay in first cost in works of 45 any extent, for frequently five or six hammers are necessary to properly perform the varied work which could readily be accomplished by one hammer having an adjustable stroke. Many hammers have a "dead-point"—that is to say, there is a certain position 50 of the distributing-valve when the tool cannot be started by simply turning on the

air-pressure. The hammer then has to be shaken or struck in order to move the valve to start the tool. Other desirable features of 55 an automatic hammer and of similar tools are simplicity and strength. The severe nature of the work to which they are put renders any complicated or delicate parts unsuitable, and such parts are rapidly put out of order by 60 dirt and are troublesome to clean.

The objects of my invention are to provide a simple, strong, economical, and efficient hammer, a hammer whose stroke shall be adjustable, a hammer having a simple positive 65 hand-valve to control the admission of the motive fluid to vary the rapidity of the stroke, whatever its length, a hammer that shall be self-starting, and a hammer having its reciprocating parts cushioned to prevent undue 70 wear and jar. These objects I obtain by the invention hereinafter described, and which consists in the improved form and arrangement of the valve for regulating the admission of the motive fluid, in the improved form 75 and arrangement of fluid-distributing valve, in the improved form of hammer and pressure-chamber, in the arrangement of the passages connecting the pressure-chamber with the chamber of the distributing-valve, and in 80 the novel means for regulating the length of the stroke of the hammer.

In the drawings which form a part of this specification, and in which like numerals refer to like parts in the different views, Figure 85 I is a side view of the tool, partly in section. Figs. II, III, IV are sections taken on lines a b, c d, and e f, respectively, in Fig. I. Fig. V is a front view of the cap or head of the tool. Figs. VI and VII are the end view and 90 side elevation, respectively, of the stroke-adjusting tube. Fig. VIII is a front view of the admission-valve. Fig. IX is a broken view showing in section the distributing-valve chamber. Figs. X to XVI are sectional views 95 illustrating the manner in which the tool operates.

In Figs. I and X to XV, inclusive, 1 is the body of the hammer. 2 is the cap or head, connected with which is the handle 3. This 100 handle is bored lengthwise, and to the bore 3^a compressed air or other means for operating the hammer is admitted through the inlet-pipe 4. The bore 3^a is connected with the

hammer-body by means of a passage 7, the admission of the compressed air or other operating fluid to the said passage 7 being controlled by means of a valve 6, the construction 5 of which will be explained hereinafter. The passage 7 connects with the passage 9 in the cap 2, which passage 9 is continued in the hammer-body 1, preferably to one side of the distributing-valve chamber 9^a, and opens into 10 the latter through a port 10. (See Fig. IX.) 8 is an extension of the passage 9, and it enters a chamber 12 by a port 8^a, Fig. IX. The chamber 12 opens at one end into and forms an extension of the distributing-valve chamber 9^a and is of smaller sectional area than the latter. (In Figs. X to XVI, inclusive, the passage 8 and others to be mentioned herein-after are, for the sake of making the operation of the hammer clear, shown in positions different 15 from those in which they are shown in the other figures.) Given a constant pressure in the passage 9, we have a constant pressure in the chamber 12. The distributing-valve chamber is preferably fitted with a liner 10^a, made 20 of suitable hardened material, to take the wear occasioned by the movement of the valve. The distributing-valve comprises the heads 11, 13, and 14, and these said heads are connected by means of the parts 15 and 15^a, the 25 said connecting parts being less in diameter than the valve-heads, so as to provide annular spaces around the valve between the said valve-heads.

16 and 17 are exhaust-ports connecting the 30 distributing-valve chamber with the outer air. In the chamber 12 there is a plunger 18, which plunger is always exerting a rearward pressure, since the fluid-pressure in the passage 8 and the chamber 12 is constant.

35 19 is an exhaust-port cut into the chambers 9^a and 12 to insure the absence of pressure on the adjacent ends of the main valve and the plunger. In the drawings I have shown the distributing-valve and the plunger 18 as 40 formed in two separate parts. Their separation is advisable for structural reasons, but they may be made in one piece, thus forming a valve having an extension of smaller diameter.

45 20 is a port through which and the passage 50 21 the distributing-valve chamber 9^a is connected with the forward end of the pressure-chamber 22.

23 is a port through which and the passage 55 24 the distributing-valve chamber 9^a is connected with the rear end of the pressure-chamber 22.

60 25 is the stroke-adjusting tube, which is provided at one end with suitable means, such as a slotted head 31, for turning it and at its 65 other and open end with a check-valve. This valve may be of any simple form and preferably consists of a ball 30, held by means of a light spring 30^a against a seat formed either in the end of the adjusting-tube 25 or in the 70 chamber in which the tube is located and adjacent to the open end of the tube. The said tube is provided in its length with openings

or ports 26, 27, 28, and 29, spaced around its circumference, and which ports may by turning the tube 25 to suitable positions be made 70 to register one at a time with the ports 32, 33, 34, and 35, respectively, the said ports 32, 33, 34, and 35 connecting the tube-chamber with the pressure-chamber 22. Upon the number 75 of ports by which it is possible to connect the interior of the tube with the pressure-chamber 22 depends the number of different lengths of stroke which the hammer may be given. For instance, if four different lengths of 80 strokes are desired the tube 25 is provided with four ports, and four corresponding ports are provided connecting the tube-chamber with the pressure-chamber. If five different 85 strokes are desired, then five sets of corresponding ports are provided, and so on. The diameter of the tube 25 should be such that the desired number of ports may be cut in it and so spaced around it that not more than one of them can afford means of communication between the interior of the tube and the 90 pressure-chamber at any one time—that is, for any one position of the adjusting-tube.

The open end of the adjusting-tube 25 is in communication through the check-valve 30 with the passage 36, which passage connects 95 with the passage 37, leading to the distributing-valve chamber, and with the passage 38, leading to the pressure-chamber extension 39.

40 is an exhaust-port connecting the pressure-chamber extension 39 with the outer air, 100 and it is located in the same vertical plane as the passage 38.

41 is the hammer, provided with a head 42 and having in its body an annular groove 43. When the hammer is in its foremost position, 105 the groove 43 forms a connection between the passage 38 and the exhaust-port 40.

44 is the head portion of a chisel or other tool inserted in a socket 45 in the end of the body 1, and 46 is an exhaust-port connecting 110 the space between the chisel and hammer 41 with the outer air.

The operation of my improved hammer is as follows: The hammer is to be set for the longest stroke, let us say. The adjusting-tube 25 is turned in its chamber until the rearmost tube-port 26 registers with its corresponding pressure-chamber port 32. Ports 33, 34, and 35 are closed, it will be seen. The rear end of the distributing-valve is open to 120 exhaust, Fig. X, by way of the passages 37 and 38 and the exhaust-port 40. The air-pressure, which is constant in the plunger-chamber 12 and which enters it by way of the passages 8, 9, and 7 and the admission-valve 6, forces the plunger against the distributing-valve and holds it in its rearward position. Air is entering the forward end of the distributing-valve chamber by the passages 7 and 9 and by that part of the port 10 125 which is not covered by the valve center head 14, and it is flowing out by the passage 21, the outlet of which into the pressure-chamber 22, however, is closed by the hammer-head 42.

Consequently the hammer is inoperative so long as the hammer is allowed to remain in this position. This is the mostadvantageous feature of my hammer, as will be seen hereinafter. When the hammer is in this position, its forward end is in contact with the tool, and the latter is not quite home in its socket. If the tool is now pressed against the work or is pulled back by hand, the hammer will be pushed to the position shown in Fig. XI. The air entering the distributing-valve chamber now finds its way by port 20 and passage 21 to the forward side of the hammer-head and causes the hammer to make its back stroke, the air behind the hammer in the pressure-chamber 22 exhausting through the passage 24, port 23, distributing-valve chamber, and exhaust-port 16. It will be seen that the passage 38 is now closed by the hammer-body to exhaust. The hammer continues its back stroke until the hammer has passed and uncovered the port 32, as shown in Fig. XII. Instantly air escapes by ports 32 and 26, tube 25, check-valve 30, and passages 36 and 37 to the rear of the distributing-valve, and since the distributing-valve is of greater sectional area than the plunger 18 the pressure on it overcomes the pressure in the plunger-chamber, and it (the distributing-valve) is forced forward. With the forward movements of the distributing-valve its head 13 closes the exhaust 16 and its head 14 opens the port 10. (See Fig. XIII.) Also the head 11 uncovers the exhaust-port 17, putting the said port in communication with the forward end of the pressure-chamber through the port 20 and passage 21. Consequently the air-pressure in front of the hammer-head escapes by the exhaust-port 17. The air-pressure on the rear end of the distributing-valve and in the passage 37 is prevented by the check-valve 30 from escaping through the tube 25, pressure-chamber, and passage 21, and it cannot escape by way of passage 38 and exhaust-port 40, for the said passage and port are closed by the body of the hammer. Pressure now enters the rear end of the distributing-valve chamber, by the port 10 and passing by way of the port 23 and passage 24 to the rear end of the pressure-chamber 22 cushions the hammer and reversing its motion causes it to make the forward stroke. The air in the passage 37 and in the rear end of the distributing-valve will hold the said valve in its forward position during the forward stroke of the hammer; but should the pressure of this air be lessened by leakage it will be reinforced as soon as the hammer-head has passed on the forward stroke the port 32, Fig. XIV, by air passing from the rear end of the pressure-chamber by way of the ports 32 and 26, the tube 25, and check-valve 30. At the completion of the forward strokes the air-pressure on the rear end of the distributing-valve escapes by the passages 37, 38, groove 43 in the hammer-body, and exhaust-port 40, and the constant pressure in the chamber 12 immedi-

ately forces the plunger 18 and consequently the distributing-valve to their rearward positions, as shown in Fig. X. The pressure-chamber 22 is now open to exhaust by way of passage 24 and exhaust-port 16. The air-port 10 is now open to the forward end of the distributing-valve chamber and air-pressure again passes through port 20 and passage 21 to the forward end of the pressure-chamber. Now when the tool is in use the hammer at the end of its forward stroke does not advance to the position shown in full lines in Fig. XV, but it only advances to about the position shown in Fig. XVI, when the forward end of the hammer strikes the head of the chisel or other tool 44, inserted in the socket 45, Fig. I; but if the hammer remained in this position the opening of passage 21 into the pressure-chamber 22 would still be closed by the hammer-head 42 and air could not enter the pressure-chamber to cause the hammer to make its backward stroke. The following is what actually takes place: The hammer advances sufficiently far to put the passage 38 in communication with the exhaust-port 40 by way of the groove 43, when the hammer strikes the head of the tool 44 and upon striking the hammer rebounds far enough to enable its head to uncover the passage 21, as shown in Fig. XI. Air under pressure at once enters the forward end of the pressure-chamber and causes the hammer to make its back stroke.

As hereinbefore stated, the fact that the hammer can under certain conditions advance so far as to let its head cover the air-inlet passage 21 is a great advantage. For instance, the tool cannot work unless the chisel is actually in use on the work, and thereby a great saving in air is effected. Suppose, for instance, that the operator forgets to close his admission-valve when he takes the tool from the work, or suppose the valve sticks, as valves used in pneumatic tools sometimes do, the hammer makes but one or a part of one stroke and stops, for the advancing hammer will upon striking the chisel-head simply drive the latter forward, and should the chisel afford sufficient resistance to cause the hammer to rebound the hammer would only make one or more strokes, when it would come to rest. Again, suppose that the chisel becomes so fast in the socket that the operator cannot remove it by hand. All he has to do is to admit a small quantity of air by the admission-valve 6, when the hammer making a stroke will loosen the chisel and then come to rest. Now when not in use on work and the hammer makes its forward stroke the forward side of the hammer-head 42 would drive up hard against the forward end of the pressure-chamber 22 were it not cushioned. I obtain a cushioning at the end of an extreme forward stroke, and so prevent jar by carrying the pressure-chamber 22 a little distance beyond the opening of the passage 21. As soon as the hammer-head

covers the said passage-opening it imprisons between itself and the end of the pressure-chamber a sufficient quantity of the air to form an effective cushion. This is clearly shown in Figs. X and XV. The hammer is cushioned on its back stroke in the following manner: The moment the hammer-head 42 passes and uncovers the port 32 the pressure on the back stroke is released and passing to the rear end of the distributing-valve chamber throws the latter, and so admits air under pressure by port 23 and passage 24 to the rear of the pressure-chamber.

The tool is self-starting—that is to say, the distributing-valve has no dead-point—and no matter what its position may be when the air-pressure is admitted through the admission-valve it will operate. Let us suppose that when the tool is about to be put in use the parts are in the position shown in Fig. XIII. The admission-valve is opened and air enters the rear of the chamber by the ports 10 and 23 and the passage 24. There is no pressure in the passage 37, and consequently on the large end of the distributing-valve, but there is pressure in the plunger-chamber 12. Consequently the pressure in the plunger-chamber throws the plunger and the distributing-valve to the rear, now putting the port 10 in communication with the port 20 and passage 21. Pressure enters the forward end of the pressure-chamber and passes out by the ports 32 and 26 and the adjusting-tube to the passage 37. As soon as the pressure in the said passage 37 is sufficiently high the distributing-valve is thrown to its forward position again and the pressure in the passage 37 holds it there throughout the forward stroke of the hammer, which is now made, since air enters the rear of the pressure-chamber by way of ports 10 and 23 and passage 24.

The question of dead-point in the valve must not be confused with the dead-point of the hammer. The valve has no dead-point; but the hammer has one, as I have pointed out and as is clearly shown in Fig. X of the drawings; but the hammer dead-point is not a necessary or unavoidable feature of the tool, though, as explained, a desirable one, for it can be eliminated at once by making the passage 21 enter at the extreme forward end of the pressure-chamber, as passage 24 enters at the extreme rear, instead of at a distance from the extreme end. The hammer-head could not then cover the end of the passage 21, and so prevent the ingress of the air.

To set the pneumatic tool for its shortest stroke, we simply turn the tube 25 in its seat until the foremost port 29 registers with its corresponding pressure-chamber port 35. The ports 32, 33, and 34 will now be closed by the body of the tube. The operation of the tool will be exactly as described above except that the hammer will only travel back far enough to uncover the port 35 instead of

the port 32, as in the case of long stroke, for as soon as the hammer-head on the back stroke passes the port 35 the air-pressure 70 will escape by the ports 35 and 29, check-valve 30, and passages 36 and 37 to the rear end of the distributing-valve. The pressure on the latter at once overcomes the pressure on the forward end of the plunger 18 and the 75 valve is forced to its forward position, as in Fig. XIII. The exhaust-port 17 is now in communication with the forward end of the pressure-chamber by way of the port 20 and passage 21, and air-pressure enters the rear 80 end of the pressure-chamber by way of the port 10 in the distributing-valve chamber, the port 23, and passage 24, checking and reversing the backward motion of the hammer.

It will be seen that we may obtain a number of different lengths of hammer-stroke in one and the same pneumatic tool, their number depending only on the number of ports, which depends in its turn upon the length of the pressure-chamber and the size of the adjusting-tube. Now for every length of stroke we shall obtain, if working under a constant pressure, one hammer-blow of definite force—that is to say, given a constant pressure and four lengths of stroke we shall obtain four 95 different hammer-blows, and the differences between these blows will not vary. Suppose we have strokes giving blows of one, two, three, and four pounds. If regulation is effected by the length of stroke alone, these 100 blows will not vary and we cannot obtain blows equivalent to the fractional parts of one, two, three, and four pounds; but such fractional blows can be readily obtained by varying the pressure of the operating fluid. 105 This is easily done by a proper manipulation of the admission-valve in combination with a proper adjustment of the length of the stroke.

In an ordinary pneumatic hammer having, 110 say, only a four-inch stroke it would be difficult to so control the admission of the motive fluid as to obtain a series of very light blows equivalent, let us say, to small fractional parts of the full stroke. To maintain such a 115 control would necessitate an exceeding delicate admission-valve, and even with such a valve the operator's touch unless highly trained would not be sufficiently delicate; but with my improved tool the operator would first 120 set the hammer to shortest stroke—say one inch—and by manipulating the admission-valve he would then be much more easily able to maintain a series of light blows, for the blows now would instead of being equivalent 125 to small fractional parts of a four inch stroke be equivalent to large fractional parts of a one-inch blow. Again, suppose that an operator supplied with a four-inch single-stroke hammer wishes to obtain on a delicate part 130 of the work a series of light blows equivalent to, say, one-eighth of full blow. If the pressure of his hand is accidentally increased by any cause, he may suddenly turn on full blow

and perhaps ruin the work. Rather than run that risk he will in the first place lay aside his four-inch hammer and use instead one of a suitable and smaller stroke. Now using 5 the short-stroke tool—say one-inch—the light blow will be more easily maintained, as it is only about half of the new full blow, and should the full pressure be turned on accidentally the resulting blow would be but little greater than the said light blow.

In my improved tool I get the benefit of a short-stroke tool by simply shortening the length of my hammer-stroke, and, as I have now described and explained, I can with this 15 adjustable-stroke tool do the work that it now requires a set of several tools to do.

The admission-valve for admitting air is in the case of most pneumatic tools of great importance, and it is not infrequently one of 20 the weak features. A weak point in many is that they require too much effort on the part of the operator to open them and to hold them open. This is usually done by the thumb alone, and the strain on the thumb 25 coupled with the vibration of the tool soon produces cramp in the hand. Another weak feature in some valves is that they are closed by means of a spring, and this spring after the tool has seen much rough usage soon 30 gets out of order and the valve refuses to close. To avoid the latter objection, my admission-valve is arranged to be closed by the pressure of the incoming air, and to avoid the former objection I nearly balance the valve. 35 It would be an easy matter to completely balance it; but it is not desirable, as then some other means would have to be provided to close the valve when released from the pressure of the thumb. Figs. I, VIII, and XI 40 show the construction and arrangement of my admission-valve. Fig. I shows the valve closing the passage 7. Fig. XI shows the passage 7 open to the incoming air, and Fig. VIII shows a front view of the valve. 5 is the thumb- 45 piece, which is connected with the valve 6 by means of a stem 47. The stem 47 passes through an accurately-drilled hole in a collar or plug 48, which collar fits closely in the bore 3^a of the handle 3 preferably and is secured 50 therein by means of a set-screw or pin 49. The valve is prevented from turning in the bore 3^a by means of a pin 50, which projects from the thumb-piece 5 into a slot 51, cut in the side of the said bore. The valve 6 consists of a low 55 cylinder nearly closed at its upper end and provided with an opening 52 to allow the air to pass from the interior of the valve to the passage 7. A part of the closed end of the valve is cut away, as at 53, to allow air 60 to pass from the interior to the upper end of the valve. Now suppose that air under a pressure of one hundred pounds to the square inch is admitted through the pipe 4 and suppose that the sectional area of the valve is one-quarter of a square inch and of the stem 47 one sixty-fourth of a square inch. The air-pressure tending to force the valve upward,

and so close it, will be twenty-five pounds, and the air-pressure on the top of the valve (due to air which has passed the cut 53 in the 70 top of the valve) and tending to open it will be twenty-three and seven-sixteenths pounds. Consequently the resultant air-pressure which closes the valve and which the thumb of the operator has to overcome in opening it is only 75 one and nine-sixteenths pounds.

If a tool the force of whose blow is only regulated by the length of the hammer-stroke is desired, the admission-valve might be omitted, for, as we have seen, the tool cannot 80 operate—that is, the hammer cannot continue to reciprocate—unless the chisel fitted in the tool is held up to its work. Merely lifting the chisel from the work causes the hammer to come to rest.

Having now described my invention, what I claim, and desire to protect by Letters Patent of the United States, is—

1. In an automatic hammer having an inlet-passage for the admission of the motive 90 fluid, a pressure-chamber, a hammer in the pressure-chamber, a valve-chamber intermediate and in communication with the inlet-passage and the pressure-chamber, a valve in the valve-chamber to control the flow of the 95 motive fluid between the valve-chamber and the pressure-chamber, and an intermediate chamber in communication with the valve-chamber and connected with the pressure-chamber by a series of ports or passages which 100 enter the pressure-chamber at points along its length; a check-valve controlling the connection between the intermediate chamber and the valve-chamber, and adjustable means located in the intermediate chamber whereby 105 the check-valve may be put in communication with the pressure-chamber through any one of the series of ports or passages entering the latter, substantially as and for the purpose described.

2. In an automatic hammer having an inlet-passage for the admission of the motive fluid, a pressure-chamber, a hammer in the pressure-chamber, a valve-chamber intermediate and in communication with the inlet-passage and the pressure-chamber, a valve in the valve-chamber to control the flow of the motive fluid between the valve-chamber and the pressure-chamber, an intermediate chamber in communication with the valve-chamber and connected with the pressure-chamber by a series of ports or passages which enter the pressure-chamber at points along its length, a check-valve controlling the connection between the intermediate chamber and 115 the valve-chamber, and means located in the intermediate chamber and adapted to be rotated to place the valve-chamber in communication with the pressure-chamber through any one of the series of ports or passages entering the latter.

3. In an automatic hammer having an inlet-passage for the admission of the motive fluid, a pressure-chamber, a hammer in the

- pressure-chamber, a valve-chamber intermediate and in communication with the inlet-passage and the pressure-chamber, a valve in the valve-chamber to control the flow of the motive fluid between the valve-chamber and the pressure-chamber, an intermediate chamber in communication with the valve-chamber and connected with the pressure-chamber by a series of ports or passages which enter the pressure-chamber at points along its length, a check-valve controlling the connection between the intermediate chamber and the valve-chamber, and, located in the intermediate chamber, a hollow ported cylinder open at one end, and adjustable to register its port with any one of the series of ports or passages entering the pressure-chamber.
4. In an automatic hammer having an inlet-passage for the admission of the motive fluid, a pressure-chamber, a hammer in the pressure-chamber, a valve-chamber intermediate and in communication with the inlet-passage and the pressure-chamber, a valve in the valve-chamber to control the flow of the motive fluid between the valve-chamber and the pressure-chamber, an intermediate chamber in communication with the valve-chamber and connected with the pressure-chamber by a series of ports or passages which enter the pressure-chamber at points along its length, a check-valve controlling the connection between the intermediate chamber and the valve-chamber, and, located in the intermediate chamber, a hollow ported cylinder open at one end and having its wall pierced by a series of ports at points along its length and adjustable to register any one of the said ports with a corresponding one of the ports or passages entering the pressure-chamber.
5. In an automatic hammer having an inlet-passage for the admission of the motive fluid, a pressure-chamber, a hammer in the pressure-chamber, a valve-chamber intermediate and in communication with the inlet-passage and the pressure-chamber, a valve in the valve-chamber to control the flow of the motive fluid between the valve-chamber and the pressure-chamber, an intermediate chamber in communication with the valve-chamber and connected with the pressure-chamber by a series of ports or passages which enter the pressure-chamber at points along its length, a check-valve controlling the connection between the intermediate chamber and the valve-chamber, and located in the intermediate chamber, a hollow ported cylinder open at one end and having its wall pierced by a series of ports at points along its length and rotatable to register any one of the said ports with a corresponding one of the ports or passages entering the pressure-chamber.
6. In an automatic hammer, having a pressure-chamber, means for supplying pressure to the pressure-chamber to cause the hammer to reciprocate in its forward direction and in a rearward direction alternately, a valve controlling the direction of the flow of

pressure to the hammer, a check-valve controlling one of the connections between the valve-chamber and the pressure-chamber, and adjustable means for automatically permitting the pressure in the pressure-chamber to act, when the hammer reaches a predetermined point on its backward stroke, on the valve to regulate the length of the backward stroke of the hammer.

7. In an automatic hammer, the combination of a pressure-chamber, a hammer adapted to reciprocate in the pressure-chamber, a valve-chamber in connection with each end of the pressure-chamber, a valve in the valve-chamber and adapted to control the direction of the flow of the air-pressure to the pressure-chamber to cause the hammer to reciprocate, a plunger of smaller diameter than the valve bearing upon one end of the valve, an air-passage arranged to admit a constant air-pressure to the end of the plunger remote from the valve, a passage connecting the other end of the valve-chamber with an exhaust-port and also with a port entering the pressure-chamber at a point intermediate its length, a check-valve controlling the said port, and the said exhaust-port being controlled by the body of the hammer.

8. In an automatic hammer, the combination of a pressure-chamber, a hammer adapted to reciprocate in the pressure-chamber, a valve-chamber in connection with each end of the pressure-chamber, a valve in the valve-chamber and adapted to control the direction of the flow of the air-pressure to the pressure-chamber to cause the hammer to reciprocate, a plunger of smaller diameter than the valve bearing upon one end of the valve, an air-passage arranged to admit a constant air-pressure to the end of the plunger remote from the valve, a passage connecting the other end of the valve-chamber with an exhaust-port and also with a port entering the pressure-chamber at a point intermediate its length, a check-valve controlling the said port, the said exhaust-port being controlled by the body of the hammer, and adjustable means for changing the position of the check-valve-controlled port entering the pressure-chamber at a point intermediate its length.

9. In an automatic hammer having a pressure-chamber, means for supplying pressure to the pressure-chamber to cause the hammer to reciprocate therein, a valve controlling the direction of the flow of pressure to the hammer, a passage connecting the pressure-chamber with the valve-chamber to allow the pressure in the pressure-chamber when the hammer is on its backward stroke to operate the valve to change the direction of motion of the hammer, and a check-valve controlling the said passage.

10. In an automatic hammer having a pressure-chamber, means for supplying pressure to the pressure-chamber to cause the hammer to reciprocate therein, a valve controlling the direction of the flow of pressure to the ham-

mer, a passage connecting the pressure-chamber with the valve-chamber to allow the pressure in the pressure-chamber when the hammer has reached a predetermined point on 5 its backward stroke to operate the valve to change the direction of motion of the hammer, and a check-valve controlling the said passage.

11. In an automatic hammer, a pressure-chamber, a valve-chamber in communication 10 with each end of the pressure-chamber, a valve in the valve-chamber controlling the direction of the flow of air-pressure to the pressure-chamber, means for operating the valve in a rearward direction, a passage connecting the rear end of the valve-chamber 15 with an exhaust-port 40 and with a chamber

having ports entering the hammer-chamber at points intermediate its length, a check-valve controlling the direction of the flow of air through the said ports, means for obstructing all but one of the said ports, and a hammer adapted to be reciprocated by the pressure in the pressure-chamber and also adapted to control the exhaust-port 40. 20

Signed at Richmond, in the county of Hen- 25
rico and State of Virginia, this 18th day of
January, 1902.

WILLIAM T. McCOOK.
